UNITED STATES PATENT OFFICE.

EDWARD G. HANNON, OF NEW ALBANY, INDIANA.

HANDLE FOR BASKETS.

No. 913,885.

Specification of Letters Patent.

Patented March 2, 1909.

Application filed February 28, 1906. Serial No. 303,480.

To all whom it may concern:

Be it known that I, EDWARD G. HANNON, a citizen of the United States, and resident of New Albany, in the county of Floyd and State of Indiana, have invented certain new and useful Improvements in Handles for Baskets, of which the following is a specification.

My invention relates more especially to handles for cheaper grades of baskets or carrying receptacles and has for its objects to provide handles for such receptacles which will be superior to the usual type of splint handle, but which will nevertheless be cheap and easy of attachment and at the same time will be collapsible or foldable for convenience when the handle is not in use, as for instance, at time of shipment.

My invention comprises a grip preferably of wood or equivalent rigid material which may be cut to the desired length in very large quantities, and straps of metal or other equivalent pliable members for connecting the ends of the grip with the basket or receptacle which may also be provided at comparatively small expense in large numbers by merely cutting a suitable grade of sheet metal into strips of suitable width and length. The rigid grips afford a comfortable hand-hold through which to support the receptacle and the pliable connecting straps, being of equal length, automatically adjust themselves under the tension imposed by the weight of the receptacle so that the handle assumes a proper position relatively to the receptacle, and retain the form into which they are bent, sufficiently to prevent disengagement of the looped end from the staple, by moving inward from the end or drawing the short end of the loop through the staple. When a pair of such handles is used, as is preferably the case in most uses for which the handle is adapted, the positions of the two handles are automatically rendered symmetrical under the weight and support the receptacle in horizontal position.

The straps are preferably secured to the grips through the medium of staples inserted a short distance from the ends, in the upper surfaces of the grips and loops formed by bending the ends of the straps upon themselves, and engaging the staples with the short ends of the loops impinged between the bodies of the straps and the end of the grip beyond the staple thereby preventing them from drawing out under an excessive load.

The sustaining power of the grips is augmented and the load on the staple largely relieved by having the grips of such length that the weight of the receptacle bends the portions 60 of the straps extending to the receptacle sharply across the ends of the grips when the handle is used. The straps are connected to the receptacle pivotally and the relation of the point of attachment and their length is 65 such that the handles may be folded over the ends of the receptacles and fit tightly thereto for convenience in nesting the baskets for shipment or packing the baskets in crates when in use and the length of the grips is also 70 selected with regard to this condition of use so as not to protrude far enough at the ends to provide objectionable shoulders or projections.

The invention will be fully understood 75 upon reference to the accompanying drawing in which—

Figure 1 is a side view of a basket having a pair of handles constructed in accordance with my invention and in position for use in 80 supporting the receptacle; Fig. 2 is a plan view of the same with one of the handles extended vertically and the other folded around the end of the basket; and Figs. 3, 4, and 5, are detail perspective views showing 85 respectively the end of the grip with its attaching staple, the loop end of one of the straps, and the attachment of the strap to the grip.

A represents a receptacle which, for purposes of illustration is shown in the form of a common type of splint basket and B represents handles applied thereto and constructed in accordance with my invention.

Each handle B comprises a grip 1, and 95 straps 2 connecting the grip to the receptacle. The grip is preferably of wood or equivalent rigid material, and provided a short distance within its ends and upon its upper surface with staples 3, preferably passing 100 through the grip and clenched upon its under side, while the straps are provided with loops 4 with short ends 5 that are passed through the staples 3 in position to be impinged between the body of the strap 2 and the ends 6 of the grip which extend beyond the staples 3. The connection of the straps 2 with the receptacle is preferably through the medium of rivets or nails 7. The points of attachment 7 are so located as to afford steady 110 support to the receptacle and the length of the straps 2 is so selected with regard to the

points of attachment as to permit the handles to fold down over the ends of the basket and cause the grips 1 to be held closely to said ends when the handles are thus folded.

5 The length of the grip 1, as will be seen in the drawing, is such that it will not protrude far enough at the ends of the basket to make objectionable projections or shoulders but is of sufficient length to cause the metal straps 10 to form a bight over the ends of the grip, under the weight of the receptacle and in addition to increasing the security of the loop, to greatly relieve the staple from the load.

Having thus described my invention, what 15 I claim and desire to secure by Letters Patent is:

1. A basket comprising a suitable receptacle, a grip, staples projecting from the upper face of the grip and arranged transversely thereto at points inward from the ends thereof, and sheet-metal straps each secured at one end to the basket and free at the other end, said straps being pliable to adapt said free ends to be passed over and through the 25 staples and clamped to the grip between the body of the strap and the end of the grip by means of the weight of the burden.

2. A receptacle having a flat grip, staples projecting upward from points thereof within its ends, and flat pliable straps pivotally

connected at one end with the receptacle and having their outer free ends passed over and through said staples, thence outwardly between the ends of the grip and the bodies of the straps in such manner as to clamp the 35 straps to the grip by means of the weight of the receptacle.

3. A basket comprising a suitable receptacle, the thin hand grip extending transversely of the basket and restricted in length 40 to within the width of the basket, and the thin pliable straps each having one end pivotally connected with the basket and the other end attached to the upper face of the grip at a point within the ends thereof, said 45 attachment being maintained automatically by the pull on the straps, said straps extending from the points of attachment outward over the ends of the grip, and downward to form a bight between which and the ends of 50 the grip, the outer free ends of the straps are clamped.

The foregoing specification signed at Louisville, Ky., this 19th day of February, 1906.

EDWARD G. HANNON.

In presence of two witnesses—

DANIEL P. YOUNG,
HENRY W. SANDERS.
